INVENTOR

BY Victor J. Evans & Co.

ATTORNEY

UNITED STATES PATENT OFFICE

1,997,490

GARMENT HOLDER

Arthur W. Hoar, Liverpool, N. Y.

Application August 6, 1934, Serial No. 738,704

2 Claims. (Cl. 211—89)

This invention relates to garment holders, and its general object is to provide a holder of the clamping type that includes cam means to cause the clamping action to increase in accordance 5 with the weight of the garment, so that it is impossible for a garment to fall therefrom regardless of its weight.

Another object of the invention is to provide a garment holder that is capable of supporting 10 a number of garments, such as a plurality of pairs of trousers, with the same efficiency as a single pair, in that it is adjustable for that purpose.

A further object of the invention is to provide a garment holder of the character set forth, that 15 is simple in construction, inexpensive to manufacture, and extremely efficient in use and service.

This invention also consists in certain other 20 features of construction and in the combination and arrangement of the several parts, to be hereinafter fully described, illustrated in the accompanying drawing and specifically pointed out in the appended claims.

In describing my invention in detail, reference 25 will be had to the accompanying drawing wherein like characters denote like or corresponding parts throughout the several views, and in which:

Figure 1 is a perspective view of the holder 30 which forms the subject matter of the present invention.

Figure 2 is an end view thereof.

Figure 3 is a fragmentary front view.

Referring to the drawing in detail, it will be noted that my garment holder includes a body 1 35 which as shown is in the form of a substantially rectangular block having secured to the ends thereof through the medium of screws or the like, the upright arms of angle brackets 2 which have their horizontal arms 3 extending forwardly from 40 the body.

The horizontal arms 3 are provided with notches 4 that extend at an inclination from the upper portions thereof and in a manner to be directed toward the body as clearly shown in Figure 1. The notches of one arm 3 are aligned with the notches of the other arm for cooperation 45 with each other, in a manner which will be presently apparent.

Cooperating with the body 1 is a roller 5 which 50 has extending from the ends thereof and eccentrically mounted with respect thereto trunnions 6 having formed on the outer ends thereof heads 7, the latter being provided with serrated peripheries and act as handles for the roller.

55 The trunnions 6 are adapted to be received

in any two cooperating notches of the horizontal arms 3 as clearly shown in Figure 1, and due to the fact that the trunnions are eccentrically mounted in the ends of the roller 5, it will be obvious that the roller acts in the capacity as 5 a cam, and this cam action is increased due to the inclination of the notches, as will be apparent upon inspection of Figure 2 which shows the roller directed toward the body 1 and disposed in contacting engagement with a strip of 10 material A to represent a garment, with the result it will be seen that the garment is clamped between the roller and the body in a manner whereby casual displacement or falling from the 15 holder is impossible.

The form of holder as shown, is primarily designed for trousers, and the body is provided with a centrally arranged recess 8 to provide a channel to receive the seams in the bottom of the leg portions of the trousers, and due to the number of notches as shown, it will be apparent that a plurality of pairs of trousers can be supported by my holder with the same efficiency as a single pair, as the notches allow for the adjustment of the roller with respect to the body to increase 20 and decrease the space between the same.

The body 1 may have openings arranged therein to receive screws for fixedly associating the same to a suitable supporting means, but of course any suitable securing means may be employed for the holder.

It is thought from the foregoing description that the advantages and novel features of my invention will be readily apparent.

I desire it to be understood that I may make 35 changes in the construction and in the combination and arrangement of the several parts, provided that such changes fall within the scope of the appended claims.

What I claim is:

1. A garment holder comprising a body having a recess arranged in the face thereof, brackets secured to the ends of the body and including forwardly directed horizontal arms having notches extending at an inclination from the top edges thereof and being directed toward the body, a roller, trunnions extending from the ends of the roller and eccentrically mounted with respect thereto, said trunnions being adapted to be received in any pair of companion notches for disposing the roller in cooperation with the body to set up a clamping action and handles secured to the trunnions.

2. A garment holder comprising a body in the 55

form of a rectangular block having a seam receiving recess in the face thereof, angle brackets having vertical arms secured to the ends of the block and horizontal arms directed forwardly therefrom, a roller, trunnions eccentrically mounted in the ends of the roller and received by the horizontal arms to provide cam means cooperating with the body to set up a clamping

action, said roller being adjustable with respect to the block and said horizontal arms provided with means to receive the trunnions to hold the roller in adjusted positions, and heads formed on the trunnions and having serrated peripheries to provide handles. 6

ARTHUR W. HOAR.
